(57) **CLAIM**

The ornamental design for a food preparation environment, as shown and described.

DESCRIPTION

FIG. 1 is a front perspective view of a food preparation environment illustrating a first embodiment of the new design;

FIG. 2 is another front perspective view of a food preparation environment illustrating the first embodiment of the new design;

FIG. 3 is a rear perspective view of a food preparation environment illustrating the new design;

FIG. 4 is a front elevational view of a food preparation environment illustrating the first embodiment of the new design;

FIG. 5 is a rear elevational view of a food preparation environment illustrating the first embodiment of the new design;

FIG. 6 is top view of a food preparation environment illustrating the first embodiment of the new design;

FIG. 7 is a bottom view of a food preparation environment illustrating the first embodiment of the new design;

FIG. 8 is left-side elevational view of a food preparation environment illustrating the first embodiment of the new design;

FIG. 9 is a right-side elevational view of a food preparation environment illustrating the first embodiment of the new design;

FIG. 10 is a front perspective view of a food preparation environment illustrating a second embodiment of the new design;

FIG. 11 is another front perspective view of a food preparation environment illustrating the second embodiment of the new design;

FIG. 12 is a left-side elevational view of a food preparation environment illustrating the second embodiment of the new design; and,

FIG. 13 is a right-side elevational view of a food preparation environment illustrating the second embodiment of the new design.

The broken lines shown in the drawings are for illustrative purposes only and form no part of the claimed design.
